UNITED STATES PATENT OFFICE.

RALPH T. SENTER, OF PHILADELPHIA, PENNSYLVANIA, ASSIGNOR TO THE NEAR-SIDE CAR COMPANY, OF NEW YORK, N. Y., A CORPORATION OF NEW YORK.

PASSENGER-VEHICLE.

1,105,706.

Specification of Letters Patent.

Patented Aug. 4, 1914.

Application filed May 22, 1913. Serial No. 769,271.

To all whom it may concern:

Be it known that I, RALPH T. SENTER, a citizen of the United States, residing at Philadelphia, in the county of Philadelphia and State of Pennsylvania, have invented 5 certain new and useful Improvements in Passenger-Vehicles, of which the following is a specification, reference being had therein to the accompanying drawing.

10 This invention relates to passenger vehicles and more particularly to street cars of that type having both the entrance and exit passageways at the same end of the car.

15 The object of the invention is to so arrange the barriers and officers' stations on the car as to provide a maximum of platform space, thereby permitting a large number of passengers to assemble on the platform before paying their fares and entering 20 the body of the car and thus facilitate the handling of traffic at congested points. To accomplish this the conductor's station is placed within the body of the car adjacent to the entrance doorway. This position not 25 only has the advantage above-mentioned but it also enables the conductor to overlook his seated load to a better advantage than when he is positioned on the platform and enables him to more effectively announce the names 30 of streets, etc.

The accompanying drawing is a horizontal sectional view of the forward portion of a street car embodying my invention showing the barriers and stations in plan.

35 In the drawing I have illustrated one embodiment of my invention and have shown the same as applied to a street car of the type shown and described in my application for patent filed July 15, 1911, Ser.

40 No. 638,635, having both its entrance and exit passageways at the forward end of the car on the same side of the longitudinal center line. As here shown the car as a whole is indicated by the reference numeral 45 1, while the platform is indicated at 2. As is usual the platform is dropped some distance below the level of the floor of the body of the car. The platform is divided by means of a barrier or rail 3 into two pas-

50 sageways 4 and 5, the former being the exit passageway and the latter being the entrance passageway. The two passageways are independently controlled by means of doors 6 under the control of the motorman 55 in a well known manner. The barrier 3

extends from the doorway to the body portion of the car and divides the opening at the forward end of the body portion into two passageways, as well as dividing the platform into two passageways. 60

The motorman's station is arranged at the forward end of the platform near that side opposite the doorway and is separated from the remainder of the platform by a barrier or rail 7. Heretofore, the conductor's 65 station has been arranged on the platform between the rail 7 and the forward bulkhead, 8, of the body portion of the car. When so arranged, however, the two stations monopolized a large portion of the platform 70 space and in order to avoid this and provide a greater space for the accommodation of passengers who are waiting to pay their fare before entering the body of the car I have provided the conductor's station within 75 the body of the car. The preferable position for this station is immediately in the rear of the forward bulkhead 8 and close to that side wall of the car opposite the passageways. In this position the conductor is 80 out of the passageway leading into the body of the car but is close to this passageway so that he can readily collect the fares as the passengers enter the car. In the present drawings this station is indicated by the 85 swinging seat 9 which is provided for the conductor. I also prefer to inclose the station in a small compartment formed by a barrier or partition 10, which may be of the height of an ordinary railing or may have 90 glass portions to enable the conductor to overlook the seated load.

It will be apparent that the arrangement of the platform is such as to provide a very large amount of available floor space, thereby 95 enabling a much larger number of passengers to find standing room on the platform than was possible heretofore. This permits of the rapid loading of the car at congested points, the passengers paying their 100 fares and entering the body of the car after the car is again in motion.

While I have shown and described one embodiment of my invention it will be understood that this has been chosen for 105 the purposes of illustration only and that I do not desire to be limited to the details of construction shown and described, for obvious modifications will occur to a person skilled in the art.

Having thus fully described my invention, what I claim as new and desire to secure by Letters Patent, is:—

1. The combination, with a car comprising a body portion and a platform, a barrier dividing said platform into separate entrance and exit passageways, a motorman's station on said platform, and a conductor's station within the body of said car near the side wall on that side thereof adjacent to the entrance passageway.
2. In a car, a body portion, a platform separated from said body portion by a bulkhead, a barrier dividing said platform into separate entrance and exit passageways, a motorman's station on said platform, and a conductor's station in the body of the car immediately in the rear of said bulkhead

and between the entrance passageway and 20 the adjacent side wall of the car.

3. In a car, a body portion, a platform separated from said body portion by a bulkhead, a barrier dividing said platform into separate entrance and exit passageways, a 25 motorman's station on said platform, and partitions within the body of said car to form a conductor's station immediately in the rear of said bulkhead and between said entrance passageway and the adjacent side 30 wall of said car.

In testimony whereof, I affix my signature in presence of two witnesses.

RALPH T. SENTER.
